UNITED STATES PATENT OFFICE.

CHARLES H. SIMPSON, OF BOSTON, MASSACHUSETTS, ASSIGNOR TO WILLIAM H. BROWN, OF SAME PLACE.

DESIGN FOR AN ELECTRIC TRANSFUSING-BATTERY.

SPECIFICATION forming part of Design No. 12,444, dated August 30, 1881.

Application filed May 4, 1881. Term of patent 3½ years.

To all whom it may concern:

Be it known that I, CHARLES H. SIMPSON, a citizen of the United States, residing at Boston, in the county of Suffolk and Commonwealth of Massachusetts, have invented and produced a new and original Design for an Electric Transfusing-Battery, of which the following is a specification, reference being had to the accompanying drawings, forming part thereof.

Figure 1 is a front elevation of my newly-designed battery; Fig. 2, a side elevation of the same, these two views being deemed necessary to fully illustrate my design.

Heretofore batteries have been made which presented, when viewed in elevation, as in Fig. 2, a circular shape.

The leading feature of my design consists of two elongated plates placed together, of even width, with rounded corners at one end and at the other end square with the slight curve, substantially as shown in Fig. 1. *a a* represent two loops.

I claim—

The design for an electric transfusing-battery herein shown and described, the same consisting of two elongated plates, of even width, with corners rounded at one end and square with the slight curve at the other end, as herein shown substantially.

CHARLES H. SIMPSON.
